UNITED STATES PATENT OFFICE.

ROBERT McCANN, OF COLUMBUS, OHIO.

DRAFT-REGULATOR FOR FURNACES.

1,380,666.

Specification of Letters Patent. Patented June 7, 1921.

Application filed March 10, 1921. Serial No. 451,250.

To all whom it may concern:

Be it known that I, ROBERT McCANN, a citizen of the United States, residing at Columbus, in the county of Franklin and State of Ohio, have invented a certain new and useful Improvement in Draft-Regulators for Furnaces, of which the following is a specification.

The object of the present invention is to provide improved and very sensitive means for automatically regulating the draft of a furnace so that the temperature of the house or building in which it is installed may be kept at a nearly uniform and desired degree. Other objects will appear from the disclosure herein.

The invention is embodied in the example herein shown and described the features of novelty being finally claimed.

20 In the accompanying drawings—

Figure 1 is a general view in front elevation.

25 Fig. 2 is an elevation of a portion of the apparatus looking at the right hand side of Fig. 1.

Fig. 3 is a detail in plan view of the controller on a larger scale.

Fig. 4 is a detail partly in section of the controller stop block operating rod.

30 Fig. 5 is a detail partly in section of a portion coöperating with the controller stop block.

35 In the views 6 designates a thermostatic bar or tube that extends through the hood of the furnace 7, said bar being rigidly held at its left hand end in a rigid frame 8 secured to the rafters 9 of the cellar. The right hand end of the thermostatic bar is connected with an upstanding lever 10 pivoted in the frame 8 so as to be oscillated by variations in the length of the thermostatic bar. The upper end of the lever 10 is in the form of a rounded tooth that engages a V-shaped notch in a block 11 on or engaged with the left hand end of a slightly flexible rod 12. The rod 12 and the block 11 are housed in a bar or frame formed with tubular portions 13 and 13^a, the block 11 working like a piston in the tubular portion 13. The block 11 is backed by a spring 14 that tends to keep the rod 12 abutted against the end of a set screw 15 in the outer end of the tubular portion 13^a. The tubular portion 13^a extends through a block 16 supported rigidly upon a hanger 8^a from

the frame 8, said block 16 being recessed as shown at 16^a. Adjustably secured by set screw 17 to the tubular portion 13^a where the latter crosses the space 16^a is a stop 18, adapted to close the space between itself 60 and one or the other of the opposed walls of the recess 16^a according to the temperature of the thermostatic bar 6. One of these walls consists of an adjustable disk or plate 19 having a rounded edge and having, as 65 shown in Fig. 5, a shank 20 provided on its opposite sides with unalined V-shaped notches 21 and 22 engaged by the tapered points of alined set screws 23 and 24 respectively so that by retracting one screw and advancing the other the disk or plate can be moved the distance desired to increase or diminish the space between it and the block 18. An important purpose of the disk 19 is to compensate for wear. Mounted on 70 one end of a shaft 25 in the block 16 is a hub 26 having opposite but axially offset blades 27, said blades being positioned by set screws 26^a so that when upon the shifting of the block 18 the hub 26 is permitted 75 to turn one blade will pass through the space at one side of the block and the other will be stopped by the block 18 closing the other of said spaces. The other end of the shaft 25 has affixed to it a grooved pulley 28 having an eccentric wrist pin 29. Around the pulley is coiled or looped a cord 30 having 80 at one end a large weight 31 and at the other a smaller weight 32. The large weight 31 is made of sufficient size to drive the shaft 90 25 and engender sufficient friction on the pulley to drive the shaft and operate the door and check while the weight 32 holds the cord taut.

Connected with the wrist pin 29 is a chain 95 33 which is passed over a pulley 34 and connected with the draft door 35 of the furnace while a rod 33^a is connected with the check valve 36 of the smoke pipe. A half of one revolution of the wrist pin causes the 100 draft door to open and the check to close and the other half of such revolution of the pin causes the draft door to close and the check to open.

Pressing upon the upper side of the tubular portion 13 is a spring actuated pin 37 for the purpose of keeping the lever 10 engaged with the block 11. The reason for this and for the provision of the flexible rod 12 is to make allowance for occasional excessive ex- 110

pansion of the thermostatic bar 6. The V-shaped engagement of the upper end of the lever 10 and the block 11 permits some slipping of the engaging surfaces.

- 5 From the foregoing it will be understood that a sufficient variation in the temperature in the hood of the furnace opens the space at one side of the block 18 and closes the other, and that the opening of the space at one side 10 permits the blade 17 at that side to pass through said space, the rotation of the shaft 25 being arrested by the block 18 closing the space at the opposite side, hence as the temperature in the furnace hood rises and falls 15 due to the alternate opening and closing of the damper and check the effect of the mechanism is to maintain in the building to be warmed a satisfactory uniform temperature. The adjustability of the rod 12 permits 20 adaptation of the apparatus to seasonal changes or so that the mean of temperature to be maintained may be varied. When the heavy weight 31 has run down and its power to operate the shaft 25 exhausted because 25 resting on the floor of the cellar it may be restored to operative position by merely lifting it to a position near the rafters as illustrated in Figs. 1 and 2. In this operation the cord merely slips around the pulley without effect by the pull of the small weight 32.

The forms of the parts can be changed without departing from the gist of the invention as claimed.

What I claim is:

- 35 1. In means for regulating the temperature of a furnace or the like having a draft controlling device, the combination of a thermostatic bar, a stop block operated by said thermostatic bar, a rotary bladed member arranged to be released and arrested by said 40 stop block and means for driving said bladed

member and operating the draft controlling device.

2. In means for regulating the temperature of a furnace or the like having a draft 45 controlling device, the combination of a thermostatic bar, adjustable means actuated by said bar, a stop block on said adjustable means, a rotary bladed member arranged to be released and arrested by said stop block 50 and means for driving said bladed member and operating the draft controlling device.

3. In means for regulating the temperature of a furnace or the like having a draft 55 controlling device, the combination of a thermostatic bar, an adjustable stop block actuated by said thermostatic bar, a rotary bladed member arranged to be released and arrested by said stop block and means for driving said bladed member and operating the 60 draft controlling device.

4. In means for regulating the temperature of a furnace or the like having a draft 65 controlling device, the combination of a thermostatic bar, a stop block actuated by said thermostatic bar, an adjustable wall coöperating therewith, a rotary bladed member arranged to be released and arrested by said stop block and means for driving said bladed member and operating the draft controlling 70 device.

5. In means for regulating the temperature of a furnace or the like having a draft controlling device, the combination of a thermostatic bar, a stop block operated by said 75 thermostatic bar, a rotary bladed member arranged to be released and arrested by said stop block, means for driving said bladed member, and means for actuating the draft controlling device having an eccentric connection with said blade driving means.

ROBERT McCANN.
